UNITED STATES PATENT OFFICE.

FRANK KINGSTON, OF ST. JOHNS, COUNTY OF KENT, ENGLAND.

MACHINE FOR CUTTING, BUNDLING, AND TYING WOOD.

SPECIFICATION forming part of Letters Patent No. 332,155, dated December 8, 1885.

Application filed August 4, 1885. Serial No. 173,547. (No model.) Patented in England November 7, 1884, No. 14,716.

To all whom it may concern:

Be it known that I, FRANK KINGSTON, a citizen of England, residing at St. Johns, in the county of Kent, England, have invented 5 a new and useful Machine for Cutting, Bundling, and Tying Fire-Wood, (for which I have made application for a patent in Great Britain, dated November 7, 1884, No. 14,716,) of which the following is a specification.

10 For preparing fire-wood—that is to say, wood used for kindling fires—rectangular blocks, which may be about nine inches wide, three inches thick, and six inches long, are cut by hand or by machinery into sticks about 15 half an inch square in section and six inches long, and numbers of these sticks are gathered together into bundles of approximately cylindrical shape, which are tied by strings and sold for use. The blocks of wood thus cut up 20 are comparatively cheap, as they are mostly waste pieces cut from the ends of planks; but the labor of cutting them into sticks, bundling the sticks, and tying up the bundles is considerable.

25 The object of my invention is to abridge this labor by the use of a machine which cuts, bundles, and ties the fire-wood without requiring any manipulation from the supply of the blocks to the removal of the tied bundles.

30 I will first describe generally the nature of the successive operations that are performed by the machine, and then describe the construction and arrangement of the machine itself with reference to the accompanying drawings.

35 The rectangular blocks, which are more easily worked if they are softened by preliminary steaming, are fed onto an intermittently-traveling chain and between two intermittently-traveling chains that grip them endwise, and 40 are by the movement of these chains advanced step by step, about half an inch at each step, through a mouth-piece, where each block is gripped, and then a knife moving diagonally across the projecting part of the block cuts off 45 a slab about half an inch thick. Each slab thus cut off is, by means of a spring guide that moves with the knife, turned over so as to lie on its face on another chain traveling at such a speed that as slab after slab is severed from the block and laid over on the 50 chain there is a continuous train of these slabs advancing toward a second rapidly-recipro-

cating knife, which, by making about six cuts during the passage of each slab under it, divides the slab into sticks each about half an 55 inch square in section. The sticks as they are thus separated are carried on side by side by a traveling chain to a chute, by which they are led into a cylinder through a slot in its side. In this cylinder there is a support receiving the sticks as they drop onto it, and descending as more and more sticks accumulate over it until the cylinder is filled. There are also on the lower side of the cylinder shakers which maintain a certain agitation of the 60 sticks, to make them lie all approximately parallel to the axis of the cylinder, which at this time is closed at one end by a sluice-diaphragm and at the other end by a plunger, which is then stationary. When the cylinder 65 is filled with sticks, a slide advances, closing the lateral slot, the sluice-diaphragm is withdrawn, leaving one end of the cylinder open, and then the plunger advances beyond the 70 sluice-diaphragm, pushing the mass of sticks 75 in the cylinder forward, so that they project rather more than half their length beyond the mouth of the cylinder. When they are thus protruded, the plunger retreats and the sluice-diaphragm closes behind the sticks 80 and the slide covering the lateral slot retreats, so that the cylinder is again ready to receive a fresh charge of sticks, many of which have accumulated above the opening while it was closed. In order to insure their dropping 85 into the cylinder, a vertical slide descends, breaking through them. While the cylinder is receiving this fresh charge the bundle that had been protruded is clamped tightly by a contracting action of the mouth of the cylinder, 90 and is tied in the following manner: an arm holding between jaws the end of a string which passes through a vessel containing melted pitchy cement, moves around the protruded bundle, thus winding on it a convolution 95 of the adhesive string, which is then released from the jaws. The arm now remaining stationary, the bundle itself is carried round by revolution of the mouth of the cylinder, winding on additional convolutions of string, 100 and then, at a certain point of the revolution, the string is again gripped by the jaws, that which had been wound on the bundle being cut from that which is held by the arm. The

bundle being thus tightly bound, the grip of the cylinder-mouth is released, the sluice-diaphragm is withdrawn, and the plunger advances, thrusting forward a succeeding bundle, 5 by which the tied bundle is pushed entirely out, the succeeding bundle taking its place to be clamped, tied, and thrust out in its turn.

As above stated, the string for tying the bundle is cemented prior to its application, 10 and consequently it will adhere to the outer pieces of wood comprising the bundle, and likewise the coils of string will adhere to each other, thereby firmly holding the bundle and rendering it unnecessary to tie the ends of the 15 string together or use other fastening devices.

The various movements mentioned above are imparted from one rotating main shaft working by suitable gearing other shafts with the necessary cranks, cams, levers, and other 20 moving parts, as will be understood on reference to the drawings.

Figure 1 is an elevation of the front side of the machine at which the wood blocks are fed. Fig. 2 is an elevation of the hinder side at 25 which the tied bundles are discharged, with the bundling-cylinder shown in longitudinal section. Fig. 3 is a transverse section showing the course of the wood through the machine. Fig. 4 is an end view of the machine. Fig. 5 30 is a plan of the machine.

Referring first to Fig. 3, in which is shown the progress of the wood through the machine, W are the wood blocks fed onto a sloping board, down which they slide until they are 35 successively engaged on the lower chain, b, and between the side chains, b', which press against the ends of the blocks. By the simultaneous intermittent motion of these chains the blocks W are advanced step by step 40 through a mouth, where a retractile serrated cheek, k², at one side advances while the chains are stationary, and holds firmly in the mouth the foremost block, which had by the movement of the chains been made to protrude 45 about half an inch beyond the mouth. While the foremost block is thus held, the first knife, K, slices off from it a slab, w, which is shown in the act of falling over. To insure its falling flat, like those w beyond, a spring-guide, k, 50 descends upon it and presses it down while the knife K ascends. When the knife K has ascended, the cheek k² is retracted, releasing the block, which is again advanced a step by the movement of the chains b b'. The cheek k² 55 again grips the block, and K cuts off another slice. Thus slice after slice is cut off, and the successive slices w are advanced by the movement of two chains, b³, below them, and b⁴, above them, toward the rapidly-re- 60 ciprocating knife K', which cuts each slab into a number of separate sticks, w', each about half an inch square in section. These sticks w' are advanced along a slope between two chains—b⁵ below and b⁶ above them—to a 65 hopper-space, where they are accumulated at w', immediately above the bundling-cylinder C, which in the figure is shown filled with

sticks w³, separated from those w² above by a slide, c. When the cylinder is emptied of the sticks w³, as will hereinafter be described, the 70 slide c is retracted, leaving the upper side of the cylinder C open under w². The sticks w² thereupon fall into the cylinder, but as they sometimes form themselves into an arch, which might prevent them from falling, a knife, c', 75 descending, breaks up the arch and insures that the sticks w² drop into the cylinder to take the place formerly occupied by w³.

On referring now to Fig. 2, which is an elevation of the back of the machine, showing the cylinder C in longitudinal section, the parts belonging to this cylinder are shown in the position occupied by them just before the cylinder is about to receive a fresh charge of sticks w³. Within the cylinder is a plunger, 80 C', having a chisel-edge at c'. When this plunger has completely retreated to the left just beyond the opening under w², the slide c is re- 85 tracted, leaving that opening free, and a sluice-diaphragm, c², descends across the cylinder, 90 closing it. The sticks then descend into the space in the cylinder between c² in front and the plunger behind; but in order to insure that the sticks shall descend in attitudes approxi- 95 mately parallel to the axis of the cylinder two 100 blades, c⁴, in the first place ascend through slots in the lower side of the cylinder, and receiving the sticks on their upper edges they gradually descend, the sticks following them; also, two other blades, c⁵, having a rapid re- 105 ciprocation vertically, act as shakers, causing the sticks to arrange themselves parallel, or nearly so, to the axis of the cylinder. When the space in the cylinder is filled with sticks, the slide c advances, separating those w³ in the 110 cylinder from those w² accumulating above, the sluice-diaphragm c² ascends, leaving the cylinder open in front, and thereupon the plunger C' advances to the right (its chisel-edge c' 115 clearing away in front of it any fragments of wood) and pushes the mass of sticks as a cylindrical bundle to the position w⁴, protruded a little more than half its length beyond the mouth of the cylinder. Leaving the bundle w⁴ in that position to be clamped and tied, as 120 will presently be described, the plunger C' retreats, c² descends, c is withdrawn, and the cylinder C receives a fresh charge of sticks. The protruded bundle w⁴ is in the first place 125 clamped. For this purpose the mouth of the cylinder, which consists of a number of seg- 130 mental pieces, c⁶, each sloped outside and fixed to the end of a blade-spring, is contracted by causing these segments to be pressed inward by means of a hollow cone, c⁷, which is pushed back by a ring, c⁸. While the bundle w⁴ is thus clamped the tying operation is effected.

A tubular arm, T, standing forward like a crank-pin from a counterbalanced arm, T', has at its end a boss, t, sloped off in front, and on a spindle which is fitted to revolve and slide longitudinally within T there is fixed another boss, t', sloped off in rear. On t and t' are fixed cutting-chisels, and on t' is also fixed a bent wire,

^{7.} The end of a string which passes through a heated pot, P, of pitchy cement being held clamped between t and t' , the arm T makes nearly a revolution round the bundle w' , thus laying round it nearly one complete convolution of the adhesive string, and then, t' separating a little from t and so leaving the spring free, the wire t' makes a revolution, wiping the string out from between t and t' and pressing it onto the bundle. The arm T now rests, while the front part of the cylinder C, which is fitted in a bearing, c^9 , and has on it a toothed ring, g , is caused to make several revolutions, the bundle w' revolving with it and winding onto itself the free string in several convolutions, and the arm T again moves a little onward until it again engages the string between t and t' , whereupon t' is retracted, so as to clamp the string, and the cutters on t and t' sever the string which is on the bundle from that which is held between t and t' . The bundle being thus tied in its clamped condition, the ring c^8 is retracted and the segments c^8 spring a little backward, releasing the bundle. ²⁵ The plunger C' now comes forward, pressing before it a fresh bundle, which extrudes the tied bundle w' from the cylinder mouth and takes its place to be clamped and tied in its turn.

³⁰ Such being the successive operations performed on the wood by the parts described, the mechanism by which these parts are caused to make their respective movements may be varied. As these movements are all of a reciprocating or intermittent character, they may generally be effected by cranks, eccentrics, cams, wipers, or their equivalents, worked by rotating shafts. I have shown in the drawings one form of such mechanism, to which, however, I make no claim. The prime moving-shaft A, driven from any suitable motor, drives by gearing, as seen best in Fig. 5, at a slower speed the second shaft, A', and this again by reducing gear drives A², and A² by reducing gear drives A³. A crank, a , on A' is linked by a connecting-rod, a' , to a slide, a^2 , moving in inclined guides a^3 and carrying the knife K, which is thus made in each revolution of A' by an obliquely-slicing action to cut off a slab, w , from the block W. Just before this cut begins a protuberance, a^4 , on the slide a^2 , acting on a roller, a^5 , depresses a lever, a^6 , which is connected to the clamping-cheek k^2 , thus causing it to clamp the block until in the back-stroke of a^2 the protuberance of a^4 again passes a^5 and the cheek k^2 moves backward. While the crank a is passing through that part of its course which retains the knife K for a time nearly stationary in its raised position, the pulleys which carry the lower feed-chains, b , and which carry the side chains, b' , and which are driven from the spindles of the former by miter-gearing b^3 , are caused to make part of a revolution, advancing the wood blocks the required distance for a succeeding cut. This is effected by a cam, F, on the back of the gear-wheel on A' acting on a crank, f , so

as to turn it partly round, while the edge of the cam F, acting on a spring, f' , presses toward the left the spindle f^2 , in opposition to a spring, thus by a friction-clutch action giving a partial revolution to a ratchet-wheel, f^3 , fixed on the spindle of the pulleys which work the chains b . Should the feed of the blocks W be obstructed, the friction-clutch yields. ⁷⁵

The chains b^2 , b^3 , b^4 , and b^5 all receive their movements from a spindle, l , which is driven by bevel-gear l' from a pulley driven by a pitch-chain, l^2 , from a chain-wheel on the shaft A'. The knife K' is suspended by two radii, $m\ m$, and is caused to sweep to and fro in a circular path determined by those radii, being linked by a connecting-rod, m' , to a crank, m^2 , on the shaft A. The piston C and the slide c of the bundling-cylinder C are both worked by racks $d\ d'$, the one, d , geared with a segment, d^2 , the other, d' , geared with a partly-toothed pinion, d^3 , on the spindle of which is a similar pinion gearing with a segment, d^4 . Both these segments are worked by cam-wipers on the shaft A³, so that the to-and-fro movements of C' and c are effected once in each revolution of the shaft A³. A longitudinal shaft, A⁴, driven by miter-gear from A³, and therefore revolving at the same speed as A³, gives the movements for the knife c', sluice-diaphragm c², the guide-blades c³, and the shakers c⁵, and for the clamping and tying mechanism. On A⁴ there are cams and wipers at A⁵ and A⁶, which work c¹, c², c⁴, and c⁵. At A⁷ a cam works a bell-crank lever, E, by which the ring that clamps the segments c⁶ is moved to and fro. At G there is on A⁴ a toothed wheel, which, through intermediate wheels, G' and G², works a large toothed wheel, G³, that is geared with the toothed ring g on the mouth of the cylinder C, causing the mouth to revolve while the bundle w' is held clamped within it, so as to wind on several convolutions of string on the bundle. On the end of the shaft A⁴ there is a mutilated wheel or wheel only partly toothed, H, with suitable wiper to bring into gear and drive the pinion H', which carries round the binding-arm T. On a disk, T², behind T', are cam projections, which give the required movements to t' and t'. ⁹⁵

Having thus described the nature of my invention and the best means I know of carrying it out in practice, I claim—

1. The combination, in a machine for cutting, bundling, and tying fire-wood, of intermittently-traveling chains for receiving and carrying a block of wood, a gripper receiving and holding the block as advanced by the chains, a slicing-knife for slicing the gripped block into slices, a knife for subdividing the sliced blocks, a carrier interposed between said knives for carrying the sliced blocks to the subdividing-knife, a bundle-forming cylinder receiving the severed slices from the subdividing-knife, a plunger acting in the cylinder for partially ejecting the bundle, and mechanism for winding a cord or string around

the bundle while held in the cylinder, substantially as described.

2. The combination, in a machine for cutting, bundling, and tying fire-wood, of intermittently-traveling chains for advancing a block of wood, a gripper for holding the block in advance of the chains, a slicing-knife for severing the gripped block into slices, a knife for subdividing the sliced block, a carrier between the said knives for carrying the sliced blocks to the subdividing-knife, a bundle-forming cylinder having an opening for receiving the subdivided blocks, a slide for covering and uncovering said opening, a plunger acting in the cylinder to partially eject the bundle, means for contracting the ends of the cylinder upon said partially-ejected bundle, a string-carrying arm for moving around the held bundle and winding thereon a string, and means for revolving the cylinder while the string carrying arm remains stationary, substantially as described.

3. The combination, in a machine for cutting, bundling, and tying fire-wood, of the intermittently-moving lower chain, *b*, and side chains, *b'*, for moving the wood step by step,

the clamping-cheek *k*, receiving the wood from the chains, the knife *K*, for slicing the wood while held by the cheek, the traveling chain *b'*, receiving the sliced blocks, a reciprocating knife, *K'*, at the end of the latter chain for severing the sliced blocks into separate parts, a bundle forming cylinder, *C*, having an opening for receiving the severed pieces from the reciprocating knife, a plunger, *C'*, acting in the cylinder to partially eject the formed bundle, a slide, *c*, for covering and uncovering the opening in the cylinder, means for contracting the cylinder on the bundle and revolving said cylinder, and a tying-arm, *T*, arranged at one end of the cylinder and having clamps *t t'* provided with cutters, substantially as described.

In testimony whereof I have signed my name to this specification, in the presence of two subscribers, this 23d day of July, A. D. 1885.

FRANK KINGSTON.
